Primary Examiner—Charles A Rademaker*Assistant Examiner*—Charles D Hanson(74) *Attorney, Agent, or Firm*—Flynn, Thiel, Boutell & Tanis, P.C.(57) **CLAIM**

The ornamental design for a main apparatus of key-phone, as shown and described.

DESCRIPTION

FIG. 1 is a top front perspective view of a main apparatus of key-phone showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
